COMBINED SPLASH-GUARD AND HOLDER FOR BATHROOM ACCESSORIES

Stephen J. Baumrind, Charleston, S.C., assignor of a fractional part interest to Larry Harold Kline

Filed Mar. 2, 1973, Ser. No. 337,388

Term of patent 14 years

Int. Cl. D6—04; D23—02
U.S. Cl. D23—69

FIG. 2

FIG. 1

FIG. 5

FIG. 4

FIG. 1 is a front perspective view of a combined splash guard and holder for bathroom accessories, showing my new design;

FIG. 2 is a rear perspective view thereof, showing the opposite end;

FIG. 3 is a partial sectional view thereof, taken along lines 3-3 of FIG. 1;

FIG. 4 is a partial sectional view thereof taken along lines 4-4 of FIG. 1; and

FIG. 5 is a partial sectional view thereof, taken along lines 5-5 of FIG. 1.

I claim:

The ornamental design for a combined splash guard and holder for bathroom accessories, substantially as shown and described.
